UNITED STATES PATENT OFFICE.

CHARLES C. CARPENTER, OF SWAMPSCOTT, MASSACHUSETTS.

SELF-SERVICE FURNISHING FOR STORES.

1,195,654.

Specification of Letters Patent. Patented Aug. 22, 1916.

Application filed May 15, 1916. Serial No. 97,509.

To all whom it may concern:

Be it known that I, CHARLES C. CARPENTER, a citizen of the United States, residing at Swampscott, in the county of Essex and 5 State of Massachusetts, have invented an Improvement in Self-Service Furnishing for Stores, of which the following is a specification.

This invention relates to a self-service outfit or furnishing for retail stores, and is directed to the production of such a service outfit as will adapt it for use in such restricted areas as would be of no possible utility under other service conditions, and, 15 additionally, will reduce to a minimum the number of salesmen required for the satisfactory attendance on customers.

The usual retail store service requires room for its immediately desired stock, 20 space for taking care of and serving customers, and an adequate force of attendants for such service, all of which adds to the retail cost of the articles sold or materially reduces the profits of the owner.

25 In many localities high rental for necessary space under present systems renders impossible the establishment of a retail store in such locality, or in the event a restricted area can be rented, it is impossible, under 30 present retail service conditions, to utilize such space, as it does not afford sufficient room for stock, salesmen, and customers.

The main object of the present invention 35 is to overcome all such objections, while at the same time give a better and quicker service to the customer, and by reducing overhead charges benefit the customer by selling a better article at the same cost, or the same grade at a reduced cost, without loss of normal profit to the owner.

40 The structural features involve the use of a seat or the equivalent for each customer, alongside of which is arranged an article elevator, the elevator well leading to a stock- 45 space or shelves arranged directly above the customer and on what might be termed a balcony mezzanine floor. An attendant on the main floor notifies the stock clerk of the wants of the particular customer, also his 50 seat number, and the stock clerk delivers the wanted commodity to the proper elevator, which he then lowers directly to the seat, or in the immediate vicinity of the seat of such customer. The attendant delivers the goods 55 to the customer, or the customer may take

the same himself, changing the same by the same method until satisfied. The main advantages of such a system or outfit reside in the facts that, only sufficient width of unoccupied space is necessary as will permit the customers reaching and leaving the seats, and the passage of the attendant in front of the customers, and the self-service feature reduces to a minimum the number of attendants necessary. The entire absence of 60 stock on the customers floor, is important as it saves space, preserves the stock, prevents loss by theft, keeps the jumble of disordered stock from the sight of customers, so that at all times an orderly appearance is 65 conserved. In fact, in connection with those commodities not requiring to be weighed or measured, a space of six feet in width is ample and a single attendant in the customer floor and a single stock clerk on the mezzanine floor may satisfactorily take care of 70 twelve or fifteen customers at one time and with even less delay than by the present service.

The invention, as illustrated, shows the 80 service outfit adapted for a retail shoe store, and the facts stated have been proven by actual installation and use.

In the drawings, Figure 1 is a front elevation of a single unit of the outfit. Fig. 2 is 85 a sectional view of the same and illustrating particularly the comparative narrow width of space required.

The self-service outfit as illustrated is designed particularly for retail shoe stores, 90 and, while the structural details to be described are adapted generally for other retail stores, it is to be understood that the outfit described may be modified by equivalent or similar details to more specifically 95 adapt it for such other retail stores.

Assuming the store space, which, for the purpose, need not be more than six feet in width, limited by side walls or partitions 1 and 2, there is arranged slightly in advance 100 of one wall, as 2, a series of columns or posts 3 of less height than the height of the space. These columns are designed to support, in conjunction with the wall 2, a mezzanine floor or balcony, of even less width than the 105 width of the main space. Below the balcony, the posts form supports for partitions 4 reaching to the wall 2, and from the floor to the balcony. There is thus formed a series of open booths 5 arranged in succes- 110

sion against the wall 2 and opening into the main space of the store, that is conveniently accessible from such space.

Each booth is a duplicate of the other, and in each is arranged at a convenient height, 5 a seat platform 6, of sufficient length for two persons, and the booth above the seat is divided, by a substantially central partition 7, into two compartments each having a seat 10 for an individual customer. The seats are preferably successively numbered throughout the store for identification purposes as will later appear. On each side of the partition 7 which extends through the balcony 15 floor and above the same, as at 8, is arranged a longitudinally-disposed runway, or well 9, open at the front at least for a portion of its length, and extending from a point above the seat 6 to a point above the balcony floor. 20 The partition 7 forms the main support for the wells, and in each well is arranged a car or cage 10, of sufficient size to accommodate the articles to be handled.

By preference, the cars or elevators may 25 be made practically self-sustaining and hence easy to move, by the use of a spring-operated supporting-cable or tape, a spring casing 11 of any well-known commercial type being secured to the top of each well, 30 the tape 12 being secured to the car. In lowering the car, the spring is wound and the car is thus assisted in returning, or the spring may be of such strength that a slight effort is necessary to force the car to its lower 35 position, while the car will rest in its upper position at such height above the balcony floor as will make it convenient for the stock clerk. It is also preferred to provide means for temporarily holding the car in its lowered 40 position, and there is shown for this purpose an arrow-headed stop 13, fixed at the proper height on the rear wall of the well, and adapted to be engaged by appropriately-formed spring arms 14 pendent 45 from the bottom of the car, the engagement holding the car within convenient reach, against the tension of the spring, until released. All available space above the balcony is to be provided with stock shelves 50 15, and the balcony is preferably provided with a front semi-wall or guard 16, by which the stock clerk is protected against falling and the stock hidden from view of the customer.

A customer entering the store, will find 55 his way to an unoccupied seat, and make known his wants to the attendant. The latter, in the retail shoe store service, having learned the requirements of the customer, will advise the stock clerk of, for example, 60 the size, width, and style of the shoe desired, together with the seat number of the customer. This information can be communicated in any usual or desired manner, such for instance as an annunciator system, telephone, speaking tube, or the like, and while

all such are contemplated, I prefer the annunciator system, as all facts can be practically given at once, and be visually indicated, therefore, the stock clerk needs no repetition, and also has the advantage of 70 some secrecy or privacy for the particular customer. The stock clerk will then select a pair of shoes from the stock shelves, which fulfil the requirements, and places the carton containing such in the elevator corresponding to the seat number of the customer, and moves the car downward until locked. The attendant or even the customer, may take the carton from the elevator. In front of each seat is a self-service shoe stand 17, which 80 forms the subject of an application for Patent #827,741, filed by me March 27, 1914. The customer tries the shoes on himself, the attendant being meanwhile busy with other customers. If a change of shoes 85 is desired, the attendant places the tried shoes in the elevator, returning the same to the balcony, using sufficient force to unlatch the car and move it upward, and advises the stock clerk of the new requirements, and the 90 operation is repeated.

The outfit described will thus permit the effective utilization of such narrow floor spaces as have been heretofore impossible of such use; will enable a single salesman and 95 stock clerk to supply the wants of all possible customers; will enable the single salesman to observe all customers, as the customers are practically waiting on themselves and thus prevent theft, which liability is 100 further removed, as each customer will, in the greater number of cases, have but a single article of sale before him at one time; will keep the jumble of disordered stock entirely from the sight of the customers, improving the appearance of the store; and will permit each customer to enter, be waited on, and leave the store without interference with or from any other customer.

The outfit has been stated to permit use 110 of narrow spaces otherwise useless for the purposes. It may be more correctly stated, that the outfit requires and in fact has as an essential characteristic a narrow space, as otherwise a number of customers greater 115 than the number of seats would congregate, and the single attendant could not observe and serve the seated customers.

I claim:—

1. A self-service furnishing outfit for retail stores, comprising a series of seats arranged in a row along one side of a comparatively narrow space, a narrow balcony for stock storage arranged above said seats, and substantially coextensive with the length of 125 the row, elevators adapted for operation between the seats and the balcony, and arranged respectively at one side of each seat.

2. A self-service furnishing outfit for retail stores, comprising a series of open front 130

booths arranged lengthwise a comparatively narrow space, seats in the booths for customers, a balcony providing stock storage space arranged above the booths, and separate elevators operating between the booths and stock storage space.

3. A self-service outfit for retail stores, comprising a series of booths arranged lengthwise and at one side of a comparatively narrow space, partitions and posts forming divisions between the booths, a balcony supported on the posts, and providing stock-storage space, seat platforms for customers in the booths, the seat platforms of

each booth being divided to provide individual seats, an elevator runway leading from a point above and convenient to each seat at a point above the balcony, and an elevator in each runway to carry articles between each particular seat and the balcony storage space.

In testimony whereof, I have signed my name to this specification, in the presence of two subscribing witnesses.

CHARLES C. CARPENTER.
